Edward Guillod

EDWARD GUILLOD, OF TITUSVILLE, PENNSYLVANIA, ASSIGNOR
TO BRYAN, DILLINGHAM, AND COMPANY.

Letters Patent No. 84,353, dated November 24, 1868.

IMPROVEMENT IN DRILLING-JARS.

The Schedule referred to in these Letters Patent and making part of the same.

To all whom it may concern:

Be it known that I, EDWARD GUILLOD, of the city of Titusville, county of Crawford, and State of Pennsylvania, have invented a new and improved Mode of Constructing Drilling-Jars, for use in oil and other artesian wells; and I do hereby declare that the following is a full, clear, and exact description thereof, reference being had to the accompanying drawings, which form a part of this specification, and in which similar letters represent similar parts in all the views.

In describing my invention, it is deemed unnecessary to narrate in detail the precise manner in which drilling-jars are used, and the severe strains to which they are at times subjected, as they have been used in drilling artesian wells for many years, and their uses and defects are familiar to all well-operators. The great desideratum in manufacturing jars is to get the largest possible area of wearing and striking-surfaces, without weakening the parts subjected to tensile strain, and, at the same time, to so construct the several parts of the jars that those parts giving and receiving the blow may not become burred or upset, and the jars thereby become inoperative.

The form of jar almost universally used heretofore, is that known as the "link-jar."

The size of the drills used in oil-wells seldom exceeds five and a half inches, and the cross-sectional area of the drilling-jars must not extend outside of a circle of about four and a half inches diameter.

In the ordinary link-jar, the entire inner working-surface of the head of the link receiving the blow cannot exceed one and a quarter inch square, or an available area of about one and a half square inch.

In the form of jars shown, I obtain, within the same arbitrary limits, a similar striking-surface of about four square inches, without lessening the strength of the parts subjected to tensile strain, and, in this form of jar, I make the several parts of wrought-iron and steel, combined in the peculiar manner hereinafter set forth.

I deem the above explanation necessary for a correct understanding of my invention.

In the drawings—

Figure 1 is a perspective view of the jars complete. Figure 2 is a vertical section of the same.

Figures 3 and 4 are transverse sections, taken on lines A B and C D.

The bright tints represent steel, and the darker tints wrought-iron, in all the drawings.

The jars represented consist of a single link, A, of the form shown, having a collar and screw-pin at the lower end, for the attachment of the drill.

A hole is drilled through the opposite end or head of the link, through which a round bolt, B, is passed, said bolt having a rectangular-shaped head, b, sliding between the vertical bars a a of the link.

The upper end of the bolt B has also a collar and

screw-pin, as shown, for attaching the "sinker-bar" of the tools.

I construct the several parts of the jars of wrought-iron and steel, in the peculiar manner shown, and in the drawings the letter s designates the portions made of steel.

In making the bolt B, I take a piece of wrought-iron, say about one and three quarters inch diameter, and weld steel around it to form the bolt-head b, the steel encasing the wrought-iron bolt as far up as may be desirable to protect its wearing-surface.

It will thus be seen that the wrought-iron extends through the bolt-head b, but that the wearing and striking-surfaces of the latter, as well as the wearing-surface of the bolt B, are of steel, the tensile strain being borne by both the wrought-iron and steel. The upper end of the bolt, including the collar and screw-pin, is of wrought-iron.

In constructing the link A, I make the upper portion of wrought-iron and steel, and the lower portion entirely of wrought-iron, as shown.

It will be seen that the outer portion of the bars a a are of wrought-iron, they being lined with steel, s s.

The wrought-iron is carried over the outer portion of the head of the link c, and the steel s is also carried over the inner portion of the same and around the bolt B, the under side of the link-head c, upon which the bolt-head b strikes, at each stroke of the drill, being of solid steel, as shown.

In working the metals of which the link A is to be made, I take a bar of steel and a bar of the best of wrought-iron, forge each of them into the general form shown in Figure 5, then carefully weld them together into a single bar. I then turn this bar over a block or anvil, corresponding nearly in width to the bolt-head b, as shown in dotted lines in fig. 5, then forge said bar into the form of the link A, weld on the shank and collar at the lower end, and drill a hole through the upper end for the insertion of the bolt B.

It will thus be seen that the fibres of the metal are continuous from either bar a, over the upper end of the link, to and throughout the opposite bar, and the blow from the bolt-head b is received upon the inner portion of the link-head, in a direction at or nearly at right angles to the fibres of the iron, thus insuring the greatest possible amount of strength and durability.

Having thus described my mode of construction,

What I claim as my invention, and desire to secure by Letters Patent, is—

The within-described drilling-jars, consisting of a single link and bolt, constructed of wrought-iron and steel, combined and applied substantially in the manner represented, and for the purposes set forth.

EDWARD GUILLOD.
